UNITED STATES PATENT OFFICE.

HENRY G. VOIGHT, OF NEW BRITAIN, CONNECTICUT, ASSIGNOR TO RUSSELL AND ERWIN MANUFACTURING COMPANY, OF NEW BRITAIN, CONNECTICUT.

BRACKET.

SPECIFICATION forming part of Letters Patent No. 734,780, dated July 28, 1903.

Application filed August 18, 1902. Serial No. 120,059. (No model.)

To all whom it may concern:

Be it known that I, HENRY G. VOIGHT, a citizen of the United States, residing at New Britain, in the county of Hartford and State of Connecticut, have invented certain new and useful Improvements in Brackets, of which the following is a specification.

My invention relates to improvements in brackets; and the objects of my improvements generally are simplicity and economy in construction and efficiency and convenience in use.

In the accompanying drawings, Figure 1 is a vertical section of the wall and shelf plates on the zigzag lines xx of Figs. 2, 3, and 4, together with a side elevation of the brace. Fig. 2 is a rear elevation of the wall-plate. Fig. 3 is a rear elevation or end view of the shelf-plate. Fig. 3½ is a broken plan view of the upper end of the brace. Fig. 4 is a plan view of the complete bracket less the outer end of the shelf-plate, which is broken off. Fig. 5 is a central vertical section of the outer end of the shelf-plate of Fig. 6, with a side elevation of the adjacent portion of the brace. Fig. 6 is a plan view of the bracket of which a portion is shown in Fig. 5.

A designates the wall-plate, B the shelf-plate, and C the brace. These parts are all made of metal by punching or blanking out and then swaging or striking up in dies. The wall-plate A is provided near its upper end with a tongue-receiving socket and two corner projections 7, and the shelf-plate is provided with a tongue 8 at its inner or rear end to be received in the socket of the wall-plate and with abutting shoulders 9 to rest immediately in front of the corner projections 7. The screw-holes 10, as shown, are countersunk by swaging or striking up, thereby forming a bur 11 on the inner face of the metal, in which the said screw-holes are formed. The tongue 8 of the shelf-plate is provided with a screw-hole 12, that registers with the upper one of the holes 10 in the wall-plate, the said screw-hole 12 being formed to receive into it the bur 11 of the screw-hole with which it registers, as shown in Fig. 1. The wall-plate is provided with a mortise 13 and slot 14, and the lower end of the brace is

provided with a tenon 15 to fit the mortise 13 and a hooked lug 16 to engage the metal at the lower end of the slot 14, as shown in Fig. 1. The parts as thus specifically described are the same as in my application, Serial No. 119,650, filed August 14, 1902, and therefore are not claimed herein excepting in connection with the features of construction herein-after described.

In my present improvements I construct the brace and shelf-plate with special reference to making one of the securing-screws serve as a positive lock to secure the brace in place, and in this bracket the wall and shelf plates may both be secured in place with the exception of one screw before the brace is inserted. In the form shown in Figs. 1 to 4 the upper end of the brace is twisted a quarter of a revolution, so as to bring the said upper end into a horizontal plane parallel to the shelf-plate, and in the said horizontal end I form a screw-hole 17 with the projecting bur 18, the said screw-hole and bur registering with the outer one of the screw-holes 10 in the shelf-plate B, as shown in Fig. 1.

In the form shown in Figs. 5 and 6 the shelf-plate is provided with a locking-slot 20 and screw-hole slot 21, the latter opening into the screw-hole 17^a, which screw-hole, in effect, forms a continuation of the said slot. The upper end of the brace C is provided with a hooked lug 22, which projects inwardly from the corner of the bracket instead of outwardly, and with a tenon 23, that fits and fills the screw-hole slot 21 at the side of the screw-hole 17^a, while the outer or front face of the said tenon 23 is beveled off, as at 24, Fig. 6, to approximately fit the bevel of an ordinary screw-head, thereby forming what is practically one side wall of a screw-hole that registers with the screw-hole 17^a.

In both of the constructions shown the wall and shelf plates may be secured in place by inserting all of the screws excepting the screw for the shelf-plate at the upper end of the brace before the brace is put in place. The brace can then be inserted by first inserting the lower end to engage the hooked lug 16 and tenon 15 in the slot 14 and mortise 13 of the wall-plate, as shown in Fig. 1. In the

construction shown in Figs. 1 to 4 the upper end of the brace is then brought into position to make the screw-hole 17 therein register with the outer screw-hole of the shelf-plate, 5 so that the insertion of the last screw through the said holes positively locks the parts in place. In the form shown in Figs. 5 and 6 after the lower end of the brace is inserted in the wall-plate, as shown in Fig. 1, the upper end of the brace may be dropped a little to bring the said upper end forwardly into a position where the hooked lug 22 will be under the locking-slot 20 and the tenon 23 under the screw-hole 17^a. The brace is then pushed 15 upwardly to pass the hooked lug through the locking-slot 20 and the tenon into the screw-hole 17^a and then pushed inwardly to engage the hooked lug with the metal at the inner end of the locking-slot 20 and slip the tenon 20 into the screw-hole slot 21, as shown in Fig. 6, when the insertion of the last shelf-screw will positively lock the parts in place, so that they cannot be disengaged so long as the said screw remains in place.

25 I am aware that prior patents show wall and shelf plates made in one piece and separable braces with one end having a plain screw-hole arranged to register with a plain screw-hole in the confronting portion of the 30 plate, against which the said brace abuts, the said end of the brace being secured by a screw passing through both of the said holes, and I hereby disclaim the same.

By my improvement the construction is simple and inexpensive, the bracket is very 35 strong and substantial, the wall and shelf plates are separable, and all but one of the screws may be inserted before the brace is put in position, and the last end of the brace to be fastened and the portion of the plate to 40 which the said end is fitted have screw-holes with interlocking recesses and projections, whereby the insertion of the final screw positively locks the parts in place.

I claim as my invention—

45 1. A bracket consisting of separable wall and shelf plates and an interlocking brace, one end of the said brace and the portion of the plate to which the said end is fitted having screw-holes with interlocking recesses and 50 projections which are locked in engagement with each other by the insertion of the last one of the holding-screws.

2. A bracket consisting of a wall-plate, shelf-plate and brace, having locking means 55 for connecting the lower end of the brace with the wall-plate and registering screw-holes at the upper end of the brace and the shelf-plate one of the said screw-holes having a bur for entering the companion screw-hole, substantially as described.

HENRY G. VOIGHT.
